(57) **CLAIM**

The ornamental design for a fender panel of a hood for a vehicle, as shown and described.

DESCRIPTION

FIG. 1 is an isometric view of a fender panel of a hood for a vehicle, showing an embodiment of our new design.

FIG. 2 is a front elevational view thereof.

FIG. 3 is a rear elevational view thereof.

FIG. 4 is a right side elevational view thereof.

FIG. 5 is a top plan view thereof.

FIG. 6 is an isometric view of a fender panel of a hood for a vehicle, showing another embodiment of our new design, which is a mirror image of the fender panel of a hood for a vehicle shown in FIGS. 1-5.

FIG. 7 is a front elevational view thereof.

FIG. 8 is a rear elevational view thereof.

FIG. 9 is a left side elevational view thereof; and,

FIG. 10 is a top plan view thereof.

Stippling and tangency lines in the drawings represent the three-dimensional contours of the design, and are not intended to indicate surface decoration. The broken lines shown in the drawings depict portions of the fender panel of a hood for a vehicle that form no part of the claimed design.
